UNITED STATES PATENT OFFICE

2,680,865

FLOOR WAXING MACHINE

Andrew F. Grissett, Hattiesburg, Miss.

Application November 24, 1950, Serial No. 197,446

1 Claim. (Cl. 15—50)

1 This invention relates to floor conditioning or waxing machines, the primary object of the invention being to provide a machine which is so constructed and arranged that it may be used in distributing liquid or paste wax onto a floor surface for conditioning the floor surface.

An important object of the invention is to provide a device of this character including a rapidly rotating brush onto which the wax is fed, and carried to the floor surface, the machine also including a polishing brush rapidly rotating and following the applicator brush to properly polish the floor and to direct the wax into the pores of the floor.

A still further object of the invention is the provision of means whereby the quantity of wax delivered to the applicator brush will be controlled by the hand of the operator gripping the handle of the device in moving the wax over the floor surface under treatment.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawing:

Figure 1 is a longitudinal sectional view on line 1—1 of Fig. 2 through the waxing machine constructed in accordance with the invention.

Fig. 2 is a sectional view taken on line 2—2 of Fig. 1.

Fig. 3 is an elevational view of the handle of the machine, a portion of the handle having been cut away illustrating the construction of the control member.

Fig. 4 is a sectional view through the vertical movable shaft on which the applicator brush is mounted.

Referring to the drawings in detail, the machine comprises a body portion indicated generally by the reference character 5. As shown the body portion is provided with vertical partitions 6 and 7 that divide the body portion into a central motor compartment 8 in which the motor 9 is mounted, and brush compartments 10 and 11.

Mounted within the brush compartment 10 is the polishing brush 12 mounted on the shaft 13 secured to the pivoted arms 14.

At one end of the polishing brush 12 is a pulley 15 over which the belt 16 operates, the belt 16 also operating over the pulley 17 operated by the electric motor.

2 At the opposite side of the housing, and disposed within the compartment 11, is the rotary applicator brush 18 mounted on the shaft 19 extended between the arms 20 that are pivotally mounted within the compartment 11.

The bearings 21 in which the shafts 22 and 23 operate, are mounted in the vertically elongated bearing openings, formed in the side walls of the body portion or housing 5. Thus, it will be noted that by raising or lowering the arms 20 the applicator brush may be moved into and out of contact with the floor surface.

Mounted within the compartment 11, and disposed directly above the brush 18, is the container 24, especially designed for containing paste wax, the container 24 having discharge openings 25, through which paste from the container 24 may pass to the applicator brush to be spread over the floor surface.

20 Operating within the container 24, is the follower 26, which follower is pivotally connected with the arm 27 through the medium of links 28, which are shown as pivotally connected with the arm 27. This arm 27 is pivotally connected to the partition 6, and extends to a point within the motor compartment. Connected with the inner end of the arm 27 is a cable 29 that extends to a point adjacent to the handle 30 disposed on the upper end of the arm 31. The cable 29 connects with the plunger 32 that is formed with a finger piece 33 which extends through the slot 34, formed in the hollow end 35 of the arm 31. Thus it will be seen that when the operator grasps the handle 30 in moving

25 the machine over the floor surface, the operator may by inserting his finger in the finger piece 33, move one end of the arm 27 upwardly, causing the link 28 to move downwardly, which forces the follower 26 against the wax in the container 24, forcing the wax onto the brush 18. Coiled spring 36 connects with the arm 27 and has one end anchored to the frame, the spring acting to normally return the arm 27 to the position as shown by Fig. 1 of the drawings.

40 **45** On one end of the shaft 19 is the pulley 37 over which the belt 16 operates which belt also operates over the pulley 15 mounted on the brush shaft 13, so that the brushes 12 and 18 will be rotated to accomplish the purpose of the invention.

50 Mounted within the motor compartment 8, is the tank 38 formed with an opening through which liquid wax is directed into the tank, the opening being closed by means of the screw cap 39. Communicating with the bottom of the tank 38, are pipes 40 and 41 which extend downwardly

therefrom, the pipes 40 and 41 extending into the distributing tank 42, which is disposed in proximity to the applicator brush 18 to deliver liquid wax thereto through the openings 43. In the bottom of the tank 38 is an opening 44 against which the valve 45 seats controlling the passage of liquid wax from the tank 38. Valve 45 is carried at the lower end of the rod 46 that extends through an opening in the top of the tank 38 and passes into the cylinder 47 that provides a housing for the coiled spring 48 that rests against the pin 49 which is secured to the rod 46, the spring acting to normally urge the valve 45 to its closed position. The upper end of the rod 46 is pivotally connected with the lever 50 mounted on the upper surface of the body portion or housing 5, the lever having a cam edge designed to engage the top of the body portion to elevate the rod 46 and valve 45, releasing wax into the distributing tank 42, when the lever 50 is moved to the position shown in dotted lines in Fig. 1 of the drawings.

In order that access may be had to the brush compartment 11, the pivoted closure 51 is provided, which may be moved to an open position on its hinge 52, when it is desired to service the brush or refill the container 24.

The closure 53 is provided at the opposite side of the body and may be swung to its open position to gain access to the interior of the body portion.

The reference character 54 indicates a horizontal partition or platform on which the motor 9 is mounted. The partition 54 is spaced from the end walls of the body portion to accommodate the wheels 55 on which the waxer is supported.

In order that the material from the container 24 will be properly spread over the brush 18, the flexible spreading blade 56 is secured to the front lower edge of the container 24, for contact with the wax.

From the foregoing it will be seen that due to the construction shown and described, I have provided a waxing machine which will carry a supply of liquid wax and paste wax to be transferred to an applicator brush, which in turn spreads the

wax over the floor surface being waxed. The machine also acts to polish the wax applied to the floor as the machine is moved over the floor surface.

It might be further stated that because of the structure of the machine, the application of the wax is manually controlled to insure the proper quantity of wax being applied.

Having thus described the invention, what is claimed is:

The combination with a floor waxing machine including a body having a control handle and a wax applying brush, of a wax dispensing means comprising a stationary container mounted directly over said brush, said container having a discharge opening through which material passes to said brush, a follower operating within said container, a pivoted arm mounted within said body, a link connected between one end of said arm and the follower, a cable connected between the handle and other end of said arm for effecting movement of the arm and follower within the container, forcing wax from said container depositing the wax on said brush, when said cable is pulled.
